UNITED STATES PATENT OFFICE

166,442

MULTITRAY SERVING RECEPTACLE

John M. Black, Chicago, Ill., assignor, by mesne assignments, to Superior Plastics Inc., Chicago, Ill., a corporation of Illinois

Application June 13, 1951, Serial No. 15,528

Term of patent 14 years

(Cl. D44—10)

To all whom it may concern:

Be it known that I, John M. Black, a citizen of the United States, residing at Chicago, in the county of Cook and State of Illinois, have invented a new, original, and ornamental Design for a Multitray Serving Receptacle, of which the following is a specification, reference being had to the accompanying drawing, forming part thereof.

Fig. 1 is a top plan view of a multitray serving receptacle showing my new design;

Fig. 2 is a side elevational view; and

Fig. 3 is a vertical cross-sectional view thereof.

The ornamental design for a multitray serving receptacle, substantially as shown.

JOHN M. BLACK.
